UNITED STATES PATENT OFFICE.

LOUIS BRUDICK, OF REDBURN, PENNSYLVANIA.

TOY BOAT.

1,150,168.

Specification of Letters Patent.

Patented Aug. 17, 1915.

Application filed February 26, 1915. Serial No. 10,753.

To all whom it may concern:

Be it known that I, LOUIS BRUDICK, subject of the Emperor of Austria-Hungary, residing at Redburn, in the county of Lycoming and State of Pennsylvania, have invented certain new and useful Improvements in Toy Boats, of which the following is a specification.

This invention relates to certain new and 10 useful improvements in toy boats.

An object of the invention is to provide a toy boat in the form of a canoe and wherein there is provided a clock mechanism associated with a figure mounted in the boat, 15 and wherein the clock mechanism is adapted to move the figure to create the impression that the boat is propelled thereby.

A further object of the invention is to provide a toy boat in the form of a canoe 20 and having pivotally mounted therein a figure toy which is moved by the clock mechanism carried by the boat and wherein the device is simple in construction and inexpensive to manufacture.

With the above general objects in view 25 and others that will appear as the nature of the invention is better understood, the same consists in the novel construction, combination and arrangement of parts to be herein- 30 after more fully described and then claimed.

In the accompanying drawing which shows the preferred embodiment of the present invention and to which reference is had herein by like characters designating corresponding parts throughout the several views: Figure 1 is a longitudinal sectional view of a toy boat built in accordance with the present invention. Fig. 2 is a horizontal sectional view taken on line II-II of Fig. 40 1, and, Fig. 3 is a detailed perspective view of the connecting mechanism arranged between the driving mechanism and the propelling oars.

Referring more in detail to the accompanying drawing, the reference numeral 10 designates the boat which is preferably in the form of a canoe as shown in Fig. 1, and is provided with the rear seat portion 11 and the bottom deck 12.

A clock mechanism is provided for the propulsion of the boat and is arranged within the housing 13 having a detachable cover 14, which housing is carried by the forward end of the deck 12. The clock mechanism 55 arranged within the housing 13 includes the vertical shafts 15 and 16 journaled within

the housing 13 while the shaft 15 extends through the cover 14 and is provided with a squared end 17 for the reception of a key by which the same may be revolved. A casing 18 incloses the lower end of the shaft 15 and houses a band spring, one end of which is secured to the said casing, while the other end is secured to the shaft. A gear wheel 19 is carried by the upper wall of the casing 18, the same being fixed to the shaft 15 and is in mesh with the lantern gear 20 on the shaft 16. A gear wheel 21 is connected to the lantern gear 20 and is in mesh with the lantern gear 22 on the other shaft 16, while 70 the gear 22 has connected thereto the fly wheel 23. It will therefore be seen that when the shaft 15 is revolved by the spring within the casing 18, vibration will be minimized by the balance wheel 23 through the 75 meshing gears as described.

The upper side edges of the boat 10 carry oar-locks 24 through which extend the oars 25 and the connecting mechanism between the oars and the clock mechanism is shown 80 in detail in Fig. 3. This connecting mechanism includes oppositely-disposed bell crank levers 26 pivoted as at 27 to the sides of the boat 10 while one leg of the bell crank is connected at its end as at 28 to the lower end of the link 29, the upper end of the link being connected as at 30 to the oar 25. A bell crank lever and link 29 is carried by each side of the boat while the lower ends of the bell cranks 26 extend through the opening 31 in the deck 12 and into the space 32 between the deck and the bottom of the boat. The lower ends are connected by the horizontal rod 33, which rod has a pitman connection 34 with the crank shaft 35, the 95 upper end 36 of which is connected to the power shaft 15 in any suitable manner, as illustrated in Fig. 1, whereby the crank 35 may be revolved to impart a rotary motion to the oars 25 through the connecting mechanism as above described, to create the impression that the figure is propelling the boat, the oars being elevated by the bell crank levers 26 and receiving a substantial rowing motion. The lower end 37 of the 100 operating crank 35 is connected to one end of the link 38, while the other end of the link is connected to an arm 39 mounted in the guide 40 carried by the bottom of the deck 12, and all positioned within the 110 space 32.

A movable figure 41 is associated with the

operating mechanism and is pivoted as at 42 between the side walls of the boat and has a downwardly projecting leg 43 passing through an opening in the deck 12 and is connected at its lower end as at 44 to the arm 39. A casing 45 is arranged within said opening and incloses a pair of compression springs 46 adapted to engage each side of the leg 43 as indicated in Fig. 2, so that the figure will be cushioned when the same moves on the pivot 42 and sudden shocks and jars will be obviated. These springs in no manner hinder the operation of the clock mechanism and are intended solely for the purpose of cushioning the figure 41. As shown, the hands and arms of the figure are hinged to the body as at 41' and project forwardly and engage the oars 25 in order to create the impression that the figure within the boat is operating the oars to propel the boat.

It is believed that the operation of the device will be readily apparent, the clock mechanism within the casing 13 rotating the crank shaft 35, which in turn operates the bell crank 26 and link 29 to reciprocate the oars 25, while the lower end of the figure is connected to the lower end 37 of the crank shaft, and the crank shaft being off-set as shown in side elevation in Fig. 1, further positively moves the figure on its pivot point. As above stated, the springs 46 cushion the leg 43 and relieve the figure 41 of undue jerky movement.

While I have shown and described the preferred embodiment of the present invention, I do not wish to confine myself to the exact details of construction shown, as vari-

ous forms, modifications and arrangements of the parts as shown may be had without departing from the spirit and scope of the invention as claimed.

What I claim as new is:—

1. A device of the class described comprising a boat, a figure pivotally mounted in said boat, clock mechanism within the boat, a crank shaft driven by said clock mechanism, connecting means between the crank shaft and the lower end of said figure, oars carried by the boat, and connected to the upper end of said figure, and connecting means between the crank shaft and oars adapted to impart a rotary rowing motion to the oars.

2. A device of the class described, comprising a boat, a housing within the boat, a clock mechanism within the housing, a pair of bell cranks arranged on opposite sides of the boat, links carried by one end of the bell cranks, oars connected to the other end of said links, a horizontal arm connecting the lower ends of said bell cranks, a crank shaft operatively connected to said clock mechanism, a link connection between said crank shaft and horizontal arm, a figure pivotally mounted in said boat, the arms of said figure being connected to said oars, a depending leg carried by said figure, and connecting means between the lower end of said leg and crank shaft.

In testimony whereof I affix my signature in presence of two witnesses.

LOUIS BRUDICK.
